US00D810372S

(12) **United States Design Patent** (10) **Patent No.:** **US D810,372 S**
(45) **Date of Patent:** **** Feb. 13, 2018**

(54) **CLEANING HEAD**

(71) Applicant: **Unger Marketing International, LLC**,
Bridgeport, CT (US)

(72) Inventors: **James M. Buckley**, New Hartford, CT
(US); **Joseph K. Patterson**, Monroe,
CT (US)

(73) Assignee: **UNGER MARKETING
INTERNATIONAL, LLC**, Bridgeport,
CT (US)

(**) Term: **15 Years**

(21) Appl. No.: **29/550,205**

(22) Filed: **Dec. 31, 2015**

Related U.S. Application Data

(63) Continuation of application No. 14/983,883, filed on
Dec. 30, 2015.

CLAIM

The ornamental design for a cleaning head, as shown and
described.

DESCRIPTION

FIG. 1 is a front, top perspective view of a cleaning head
according to the present disclosure;

FIG. 2 is a rear, bottom perspective view of the cleaning
head of FIG. 1;

FIG. 3 is a first side view of the cleaning head of FIG. 1;
FIG. 4 is a second, opposite side view of the cleaning head
of FIG. 1;

FIG. 5 is a front view of the cleaning head of FIG. 1;

FIG. 6 is a rear view of the cleaning head of FIG. 1;

FIG. 7 is a top view of the cleaning head of FIG. 1; and,
FIG. 8 is a bottom view of the cleaning head of FIG. 1.
The broken lines in the figures represent portions of the
cleaning head that form no part of the claimed design.

1 Claim, 6 Drawing Sheets
